A. CARDENAS Y HUERTA,
PROCESS FOR THE MANUFACTURE OF TOYS,
FILED JAN. 16, 1920.

Inv. No. 1,441,582
Antonio Cardenas y Huerta,
By - P. Amigo, Atty

UNITED STATES PATENT OFFICE.

ANTONIO CARDENAS Y HUERTA, OF HABANA, CUBA.

PROCESS FOR THE MANUFACTURE OF TOYS.

Application filed January 16, 1920. Serial No. 351,850.

To all whom it may concern:

Be it known that I, ANTONIO CARDENAS Y HUERTA, a citizen of the Republic of Cuba, and a resident of Habana, Cuba, have invented certain new and useful Improvements in Processes for the Manufacture of Toys, of which the following is a specification.

This invention relates to the manufacture of toys and its main object is to provide a process for the manufacture of toys made of a material such as cardboard, thick paper, paper paste or the like, which process permits the rapid construction of the toys and renders them strong and durable, thus obtaining an important reduction in the cost thereof.

The present processes for the manufacture of cardboard toys are distinguished in that the members or parts thereof are made individually and separately and then assembled together to form the animal or figure which constitutes the toy. It is evident that through such a process the completed toy can not attain the required strength.

According to the process forming the subject matter of my invention the toy is constructed by moulding it in sections, each one of which comprises various parts or members of the toy and uniting said sections together, thus completing the toy. Preferably there are only two sections, each one comprising one half of the toy, and in this manner the maximum degree of resistance is attained by so simplifying the construction of the toy.

The invention is described with reference to the figures of the annexed drawings, in which:

Fig. 1 is an inner view of the half part of a mould arranged for making a toy consisting of a little horse.

Fig. 2 is a cross section on line 2—2 of Fig. 1.

Fig. 3 is a front elevation of the two halves of the toy after being moulded, and

Fig. 4 is a front elevation of the completed toy.

In the drawings 1 indicates the half part of a mould of any material, preferably gypsum or cement, constituted by various sections 1' which are properly assembled together so as to form the whole illustrated in Fig. 1. Having thus prepared the half of the mould, the cardboard or thick paper to be used is cut into pieces and put into a proper receptacle containing clean water in order to wet and

soften them so that they may attain the consistency of a plastic mass. When the mass reaches this condition there is added thereto a light starch of corn or wheat.

The plastic mass thus obtained is poured into a half of the mould and is pressed down therein with a mallet or by hand or in any other manner as might be deemed proper so that such plastic mass may form a layer fitting into the alto or bas-reliefs of the mould half for reproducing the figure and the accessories or harness with which it is dressed, such as for instance the saddle 4 (Fig. 1). Then the various constituting sections of said mould half are separated in order to take out the moulded material and to subject the same to a drying operation, either through artificial heat or by the action of the sun and air, thus hardening the plastic mass thereof which hardening is aided and completed by the starch previously added.

This operation is repeated exactly in the same manner in the other half of the mould for constructing the other half of the toy, these halves being completed as illustrated in numerals 2 and 3 of Fig. 3. Then it is proceeded to bind together the two halves of the toy and this is done by applying any kind of adhesive to the coinciding borders of the halves, and thereupon is applied thereto a layer of mucilaginous liquid mixture such as white glue and Spanish white, and once this layer dries, the outer surface of the toy is polished up to deprive it of the roughness thereon, thus the toy being finished and ready for being painted and decorated in the desired manner.

The completed toy is then mounted on a wheel platform 5, as illustrated in Fig. 4, and secured with screws 6 to said frame the hoofs 7 of the play horse which constitutes the toy in the present illustration of the invention.

It is obvious that in the manner above described all kind of articles to be used as toys can be manufactured, and that same can be made stronger if they were of larger dimensions. Also it is evident that many changes and modifications can be made in the process which will fall within the scope of the appended claim.

What I claim is:

A process for manufacturing toys which consists in forming a plastic mass by wetting

and softening pieces of cardboard or thick paper, adding to said mass a light starch, pouring the whole into sectional moulds where there is represented in alto and bas reliefs the figure with its accessories and dressings, pressing the plastic mass to adapt it to said alto and bas reliefs of the mould;

taking out the moulded mass and subjecting the same to a drying operation in order to harden it, and uniting the moulded parts to 10 constitute the toy.

In witness whereof I affix my signature.

ANTONIO CARDENAS y HUERTA.
